Filed July 30, 1959, Ser. No. 830,590

4 Claims. (Cl. 26—12)

This invention relates to an apparatus for cutting the floating loops formed transversely in a base fabric in order to form tufted pile fabric, and more particularly to a mechanism for cutting floating loops which have been woven parallel to the weft of the fabric.

Heretofore, floating loops have been formed primarily longitudinally or parallel to the warp of a woven fabric, necessitating the use of cutting mechanisms which travel transversely of the fabric and simultaneously cut the warpwise loops disposed in transverse rows. Such mechanisms, of necessity, have been quite complicated because they not only must be able to cut the loops but must also move transversely of the fabric in opposite directions and longitudinally with a longitudinally moving fabric in order for a mechanism to remain in alignment with each transverse row during the cutting operation.

It is therefore an object of this invention to overcome the disadvantages enumerated by forming the floating loops parallel to the weft of the fabric and providing a much simpler cutting mechanism for cutting the loops along longitudinal rows.

Another object of this invention is to provide a cutting mechanism which may be supported in a stationary position transversely of the fabric as the fabric is moved to feed the loops toward the cutting mechanism.

Another object of this invention is to provide an apparatus for cutting floating loops which may or may not be employed as a part of the loom for weaving the fabric incorporating the floating loops.

Another object of this invention is to provide a floating loop cutting mechanism of novel construction incorporating a shoe for engaging and guiding the loops in each longitudinal row of a fabric to a looper element cooperating with a reciprocating knife for severing the loops in order to form tufts in the fabric.

Another object of this invention is to provide a floating loop cutter incorporating a scissors-action for more effectively severing the floating loops to form tufts in a base fabric.

Further objects and advantages of the invention will be apparent from the following description taken in conjunction with the drawings, wherein:

Fig. 1 is a side elevational view of the invention with the end housing and bearings removed;

Fig. 2 is a fragmentary top plan view of the left end of the machine;

Fig. 3 is an enlarged view of the cutting mechanism disclosed in Fig. 1;

Fig. 4 is a section taken along the lines 4—4 of Fig. 3; and

Fig. 5 is an enlarged section taken along the lines 5—5 of Fig. 1.

Referring now to the drawings in more detail, Fig. 1 discloses the apparatus or machine having a bed frame 10 supported by front standards 11 and rear standards 12, only the standards on the left side of the machine being

shown. Mounted transversely across the front standards 11 is a shaft 13 supporting a roll of woven base fabric 14 in which floating loops 15 have been formed parallel to the weft of the fabric and in which the loops 15 are aligned to form substantially parallel longitudinal rows. The fabric 14 is fed from the shaft 13 across the front feed roll 17 where the fabric travels substantially horizontally across the bed frame 10 upward around the lower rear feed roll 18 and over the upper rear feed roll 19 and rod 20 for any desired further disposition such as cutting, folding, rolling or packing.

Front and rear shafts 22 and 23 are supported transversely of the bed frame 10 for supporting respectively front and rear sprockets 24 and 25. The sprockets 24 and 25 support and drive a continuous chain 26 at each lateral edge of and below the fabric 14. The chain 26 is provided with a plurality of spaced shoes 27 having outwardly extended spikes 28 for engaging the opposite bottom edges of the fabric 14 to support and maintain the fabric in transverse tension as it is fed longitudinally through the machine.

Supported between the rear standards 12, only the left one of which is disclosed, is a transverse channel member 30 supported above the bed frame 10. Depending from the channel member 30 at spaced intervals across the machine are a plurality of bearings 31 in which a rock shaft 32 is journaled. A greater portion of the length of the rock shaft 32 has a chordal section removed in order to provide a flat surface for receiving the transverse supporting plate 33. Fixed to the transverse supporting plate 33 is a transverse knife holding block 34 having a plurality of transversely spaced recesses 35. Each recess 35 is adapted to snugly receive a mating pin 36 fixed to and extending rearwardly from a substantially rectangular knife holder 37. A thin elongated substantially rectangular knife blade 38 is adapted to be slidably and longitudinally adjusted in the knife holder by means of a set screw 39. The bottom 40 of the knife blade 38 is sharpened and positioned slightly above the path of the fabric in order that it may engage the floating loops 15 when they are raised in cutting position. The knife blade 38 is reciprocated through a limited arc in a vertical plane by means of an eccentric 42 mounted on a continuously driven rotary shaft 43. An eccentric strap 44 reciprocated by the eccentric 42 is adjustably pivoted to the end of a crank arm 45 by means of a pin 46. The other end of the crank arm is fixed to one end of the rock shaft 32, as best disclosed in Figs. 1 and 2. The drive shaft 43 may be driven through any convenient means such as the pulley 47, belt 48 and motor 49.

Transversely mounted between the rear standards 12 and slightly above the fabric 14 is a transverse loop-forming support bar 52. Fixed to the front of and depending below the support bar 52 is a shoe block 53. A plurality of loop-supporting shoes 54 are arranged parallel to each other pointing toward the front of the machine, or in the direction opposite the direction of fabric feed, and each is supported at its rear end to the shoe block 53 by a set screw 55. There are as many shoes 54 as there are longitudinal rows of floating loops 15, each shoe being aligned with a corresponding row of loops and positioned to pass between the loops 15 and the fabric 14 as the fabric is fed to move the loops 15 upon the shoes 54.

The shape and the function of the shoes 54 are best disclosed in Figs. 3 and 4. Each shoe 54 has a substantially flat bottom to hold down and yet permit the free passage of the fabric 14 therebeneath as the smooth rounded blunt toe 56 of the shoe is introduced within each loop 15 in a corresponding row as it moves toward

the rear of the machine. Each shoe 54 contains an elongated slot or groove 57 along its longitudinal axis.

Of substantially lesser width, having a uniform thickness and adapted to fit within the groove 57, is a looper element 58. No part of the looper element 58 is positioned to depend below the bottom of the groove 57. The front of the looper element 58 is slightly pointed at 59 and spaced proximate to the front end of the groove 57. The top surface 60 of the looper element slopes upwardly toward the rear of the machine in order to provide a substantially continuous surface over which the loop may be fed from the front portion of the shoe 54 to a raised position on the looper element 58 in position for cutting by the reciprocating blade 38. The rear portion of the looper element 58 extends upward and is supported in a looper block 61 by means of a set screw 62. The looper block 61 is fixed to the front portion of the shoe block 53 so that the shoes 54 and the looper elements 58 are all stationarily and relatively fixed to each other. The width of the groove 57 is sufficient not only to permit the reception of the looper element 58 but also the knife blade 38, which, although it is tensioned against the edge of the looper element 58, is free to reciprocate longitudinally thereof within the groove 57.

As best disclosed in Fig. 3, the blade edge 40 is not only sharpened, but slopes slightly downward toward the rear of the machine and intersects the upper surface 60 of the looper element in both extreme reciprocating positions as disclosed by the solid and dashed lines in Fig. 3. Thus, the oppositely sloping surfaces of the knife blade edge 40 and the upper looper surface 60 is so constructed and positioned that the resulting severing action resembles that of a pair of scissors and has been found to be extremely smooth and effective under conditions of rapid reciprocation of the knife blade 38 and the continuous movement of the fabric 14.

The sprocket shaft 22 may be driven by any suitable means, such as the motor 65, reduction gear box 66 and chain 67, in order to continuously drive the fabric carrying chains 26.

It can thus be seen that a machine for cutting floating loops formed transversely of a woven base fabric has been developed which employs a minimum number of parts of simple construction. Moreover, the cutting mechanism is adapted to perform its function in a stationary position without involving the complicated timing problems of moving the cutting mechanism relative to the movement of the fabric.

Whereas a cutting apparatus of the type which travels transversely of a woven fabric to cut the loops as they are formed on a loom will produce only about twelve bedspreads per day, the machine constructed according to this invention will sever enough loops to form forty bedspreads of the same size per hour.

It will be apparent to those skilled in the art that various changes may be made in the invention, without departing from the spirit and scope thereof, and therefore the invention is not limited by that which is shown in the drawings and described in the specification, but only as indicated in the appended claims.

What is claimed is:

1. An apparatus for cutting floating loops which have been woven weftwise in a base fabric to form rows of

loops longitudinally of the fabric comprising, a frame for supporting said fabric, means for moving said fabric longitudinally of said frame, a loop forming bar stationarily mounted on said frame and spaced proximate to and above said frame, a plurality of elongated shoes mounted on said loop forming bar, each of said shoes being in alignment with and adapted to engage the loops in a longitudinal row, each of said shoes having an elongated groove, a looper element for each shoe mounted on said loop forming bar, said looper element depending into said groove in a corresponding one of said shoes, the upper surface of said looper element sloping gradually upward in the direction of fabric movement and being adapted to receive and raise the loops formed upon the corresponding shoe, a knife blade for each looper element mounted above said fabric supporting frame, each knife blade being received in a corresponding one of said grooves and tensioned against a looper element to reciprocate longitudinally within said groove, and means for reciprocating said knife blades in unison within said grooves to sever said loops formed on said looper elements.

2. The invention according to claim 1 in which the means for reciprocating said knife blades comprises a rock shaft rotatably mounted transversely above said fabric supporting frame, all of said knife blades being fixedly mounted to said rock shaft, and eccentric means for reciprocating said rock shaft.

3. The invention according to claim 2 in which each knife blade has a cutting edge sloping downward in the direction of fabric movement and intersecting the upper surface of its corresponding looper element in order to effect a substantial scissors action in severing the loops upon the looper element.

4. An apparatus for cutting floating loops formed transversely in longitudinal rows in a base fabric comprising, a stationary shoe having a substantially flat bottom adapted to pass substantially flush over said fabric and through the loops in a longitudinal row when said fabric is moving longitudinally, an elongated groove formed longitudinally in said shoe, a stationary looper element mounted longitudinally in said groove and spaced from at least one side of said groove, the upper surface of said looper element sloping upward away from the loop receiving end of said shoe to receive and raise loops formed on said shoe, a separate reciprocable knife blade tensioned against said looper element to move longitudinally within the space between said looper element and said one side of said groove, means for moving said fabric longitudinally beneath said shoe to feed loops over said shoe and upon said looper element, and means for reciprocating said blade to sever loops on said looper element.
